1.25 : Perspective view of the powder feeding machine for weighing in a configuration of use

This article is a powder feeding machine for weighing that stores a powder particle material including foods, chemicals, pesticides, and resin materials in stockers mounted around a centrally located main body and feeds the powder particle material to a container that is placed on a weighing device; as shown in each of reference views in usage state, a

(Continued)

weighing device can be provided with a conveyor which carries the containers through the underside of the main body. The broken lines show portions of a powder feeding machine for weighing that form no part of the claimed design.
